UNITED STATES PATENT OFFICE.

ALFRED M. DEMUTH, OF CHICAGO, ILLINOIS.

DESIGN FOR A COOKER.

• 54,607.

Specification for Design.

Patented Mar. 9, 1920.

Application filed August 11, 1919. Serial No. 316,880. Term of patent 14 years.

To all whom it may concern:

Be it known that I, ALFRED M. DEMUTH, a citizen of the United States, residing at Chicago, in the county of Cook and State of Illinois, have invented a new, original, and ornamental Design for a Cooker, of which the following is a specification, reference being had to the accompanying drawing, forming a part thereof.

The figure is a perspective view of a cooker showing my new design.

I claim:

The ornamental design for a cooker as shown.

ALFRED M. DEMUTH.
